UNITED STATES PATENT OFFICE.

GEORGE ALEXANDER BURROUGHS AND WILLIAM GRANT, OF SUDBURY, ONTARIO,
CANADA.

ELECTRIC WATER-HEATER.

1,175,234.

Specification of Letters Patent. Patented Mar. 14, 1916.

Original application filed January 9, 1913, Serial No. 741,095. Divided and this application filed October 18, 1915, Serial No. 56,584.

To all whom it may concern:

Be it known that we, GEORGE ALEXANDER BURROUGHS and WILLIAM GRANT, both of Sudbury, in the Province of Ontario, Dominion of Canada, have invented certain new and useful Improvements in Electric Water-Heaters, of which the following is the specification.

This invention relates to improvements in electric water heaters adapted to be utilized in conjunction with the electric heating element described in my patent application Serial No. 741,095, from which the present application has been divided, and the objects of the invention are to provide a simple and effective form of heater in which the water will be readily and quickly heated.

A further object of the invention is to construct a heater which will remain hot for a considerable time after the current has been turned off from the heating element.

A further object still is to adapt the heater for the heating of water in heating systems of dwellings and the like, and it consists essentially of the improved construction hereinafter described in detail in the accompanying specification and drawings.

In the drawing, Figure 1 is a sectional elevation of an embodiment of the invention as applied to a hot water furnace. Fig. 2 is an elevation of an alternative embodiment of the invention. Fig. 3 is a sectional detail through the heating chamber of the alternative form of the invention, the heating element being in elevation.

Like characters of reference refer to like parts in the several figures.

Referring first to the form shown in Fig. 1, A represents an ordinary hot water furnace embodying the present invention and includes the header B which, as far as the present invention is concerned, forms the water heating chamber. This header extends transversely across the rear of the furnace and communicates with the outlet pipes 10 of the water circulating system which lead to the radiators.

Following the present invention the water heating chamber B is constructed in the form of a vacuum chamber, that is to say it is provided with double walls 11 and 12, the space 13 between which is exhausted. The header B is adapted to house an electric

heating element C which extends longitudinally through the said header and is supported from plugs 14 and 15 in the ends thereof.

It will be seen that a space 25 is provided between the coil C and the wall of the chamber B and in this space the water may circulate and be heated and after the current is turned off the water within the chamber B, owing to the vacuum between the double walls, will be kept at a high temperature. It will be found most convenient to use this form of device as an auxiliary to the furnace, that is to say, the main body of water may be brought to a suitable temperature by the furnace itself and then the fire in the furnace may be either kept low or allowed to go out, the water in the coils being maintained at the proper temperature by the operation of the resistance coil.

In the embodiment of the invention illustrated in Figs. 2 and 3, the furnace is dispensed with and the heating chamber B' is cylindrical in form and provided with an inlet 30 to which the return pipes 31 from the heating system are connected and an outlet 32 to which the main 33 leading to the radiators is connected.

The water heating chamber is provided with double walls 34 and 35, the space between which is evacuated. The electric heating element C' extends longitudinally of the chamber B' and is similar in form to that shown in Fig. 1, the passage of water on the interior of the chamber to the main pipe 33 taking place through a perforated sleeve 37 which connects the two. The arrangement is preferably such that the heating coil C' may be withdrawn through the bottom of the chamber B' by removing the plug 38.

As many changes could be made in the above construction and many apparently widely different embodiments of my invention, within the scope of the claims, constructed without departing from the spirit or scope thereof, it is intended that all matter contained in the accompanying specification and drawings shall be interpreted as illustrative and not in a limiting sense.

What we claim as our invention is:—

1. In a device of the character described, a water circulating chamber having inlet and discharge conduits, a vacuum jacket

- surrounding the said chamber, an electric heating element in the water circulating chamber, and a perforated sleeve adjacent to the discharge conduit designed to engage
5 the heating element.
2. The combination with a hot water furnace having a header from which circulating pipes lead and an electric heating coil extending through the header, a removable
10 plug in the end of the header operatively supporting the heating coil, and a vacuum chamber surrounding the heater, the said
- plug being adapted to obviate axial movement of the heating element and hold the same concentrically arranged to the vacuum 15 chamber.
- In witness whereof we have hereunto set our hands in the presence of two witnesses.
- GEORGE ALEXANDER BURROUGHS.
WILLIAM GRANT.
